ATTORNEY

UNITED STATES PATENT OFFICE

108,011

DESIGN FOR A SERVING TONGS

John Clark Brown, New York, N. Y.

Application September 15, 1937, Serial No. 71,641

Term of patent 14 years

To all whom it may concern:

Be it known that I, John Clark Brown, a citizen of the United States, residing in New York, in the county of New York and State of New York, have invented a new, original, and ornamental Design for a Serving Tongs, of which the following is a specification, reference being had to the accompanying drawing, forming part thereof.

In the drawing, Figure 1 is a side view and Figure 2 is an edge view of a serving tongs, showing my new design.

I claim:

The ornamental design for a serving tongs, as shown.

JOHN CLARK BROWN.
